(57) **CLAIM**

The ornamental design for a fuel pump, as shown and described.

DESCRIPTION

FIG. 1 is a front, right, and top perspective view of a fuel pump, showing our new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view taken from the encircled portion labeled “9” in FIG. 2; and,

FIG. 10 is an enlarged view taken from the encircled portion labeled “10” in FIG. 3.

The dot dash broken lines in FIGS. 2, 3, 9, and 10 denote the boundaries of the enlarged areas and form no part of the claimed design. The evenly dashed broken lines in the drawings depict portions of the fuel pump that form no part of the claimed design.
